UNITED STATES PATENT OFFICE.

ALBERT B. TENNEY, OF EVERETT, MASSACHUSETTS.

VARIABLE-MOTION MECHANISM.

SPECIFICATION forming part of Letters Patent No. 697,041, dated April 8, 1902.

Application filed May 24, 1901. Serial No. 61,720. (No model.)

To all whom it may concern:

Be it known that I, ALBERT B. TENNEY, a citizen of the United States, and a resident of Everett, in the county of Middlesex and State of Massachusetts, have invented a new and useful Improvement in Variable-Motion Mechanism, of which the following is a specification.

My invention relates to the class of devices used for imparting movement to a shaft at different rates of speed; and the object of my invention is to provide a device of this class that shall have a greater efficiency than devices of the prior art and one that shall also simplify the construction. A device by means of which these objects may be attained is illustrated in the accompanying drawings, in which—

Figure 1 is a view in side elevation of a portion of a metal-working machine, showing the variable motion attached thereto, the latter being shown in side elevation. Fig. 2 is a detail view, in longitudinal section, through the device.

In the accompanying drawings the letter *a* denotes a portion of the frame of a metal-working machine, on which frame is supported a cam-shaft *b*, bearing a cam-wheel *c*. This cam-shaft is driven by means of a worm *d*, meshing with a worm-wheel (not shown) secured to the cam-shaft *b*. The worm *d* is secured to a driving-shaft *e*, which is supported in the usual manner in bearings *a'* on the frame of the machine.

All of the parts just described are of usual and well-known arrangement and construction, my invention relating particularly to the means for driving the shaft *e* at different rates of speed.

The means for controlling the movement of the shaft *e* at different rates of speed consists of a cam *c'*, secured to the cam-wheel *c* and operating upon a stud on the under side of a rocking lever *f*, pivoted on a web *a'* on the frame of the machine. One arm *f'* of this lever engages a sliding bar *g*, to the end of which is secured a yoke *g'*. This yoke overarches a portion of the mechanism, and the end of the yoke rests in a circumferential groove in a clutch member *h*, which is splined to the shaft *e*. This clutch member bears pins *h'*, secured to its face.

A driving-pulley *i* is loosely mounted on the shaft *e*, and the hub *i'* of this pulley *i* forms a clutch member coöperating with the clutch member *h*. In the hub *i'* are located pins *i''*, that project from the face of the hub and coöperate with the pins *h'* in the clutch member *h* to connect the parts. These pins *i''* are seated on springs *i'''*, so that when the clutch member *h* is moved toward the pulley *i*, as by means of the cam *c'*, lever *f*, bar *g*, and yoke *g'*, should the pins lie opposite each other the pins *i''* may retreat within the sockets in the hub *i'* until the part *h* has been rotated sufficiently to allow the pins to slide past each other, and thus avoid any breaking of the pins or other parts of the machine in the operation. When the pins are in engagement with each other, the shaft is driven at the same rate of speed as that at which the pulley *i* is turning. When, however, it is desired to drive the shaft at a different rate of speed, the following mechanism is put into operation:

A ratchet-wheel *k* is loosely mounted on the shaft *e*, and a pawl *l*, pivoted to an upward-projecting part from the web *a''*, is adapted to engage the ratchet to prevent backward movement thereof. This ratchet has a hub *k'*, on which is loosely mounted a plate *m*. This plate bears a stud *m'*, on which is loosely mounted a pinion *n*, the pinion being free to rotate on the stud. This pinion is in mesh with an internal gear *q*, formed on a flange *q'* from the pulley *i*, and the pinion also meshes with a pinion *o*, secured to the hub *k'* of the ratchet *k*. The pinion *n* also meshes with a pinion *p*, keyed to the shaft *e*. The pinions *o* and *p* have a different number of teeth, in the form shown the pinion *p* having one more tooth than the pinion *o*.

In the operation of the device when it is desired to rotate the shaft *e* at a high rate of speed the cam *c'* is so located as to swing the lever *f*, whereby the yoke *g'* is moved to cause the pins on the clutch member *h* to engage the pins *i''* in the clutch member *i'*. When these parts are engaged, the shaft *e* is rotated at the same rate at which the pulley *i* is rotated and in the same direction. When it is desired to operate the shaft at a slow rate of speed, the cam *c'* is caused to move the yoke *g'*, so that the pins are disengaged,

the pawl *l* being in engagement with the ratchet *k*. The tendency is to now move the ratchet *k* backward; but it being held by the pawl *l* the shaft *e* is caused to rotate in the 5 same direction as the pulley *i*, but at a very much slower speed.

The sliding bar *g* is engaged by the arm *f'* of the rocking lever *f*, the end of the arm being located between the stops *g*² *g*³. One at 10 least of these stops is adjustably secured to the bar in the form shown herein, the stop *g*² being so secured, a bolt *g*⁴ passing through a longitudinal slot in the bar, by means of which the desired amount of adjustment may 15 be secured. This adjustment of the stop provides means whereby any variation between the dogs on the cam-wheel for throwing the clutch in and those for throwing the clutch out that may have occurred for any reason 20 may be equalized. This adjustment is also found advantageous in renewing the pins in the clutch parts to compensate for any variation in the pins.

I am aware that it is not new to provide a 25 device of this character with a pinion rotating about and in mesh with the teeth of two other pinions bearing a different number of teeth and one of which is secured to a shaft and the other free to rotate thereon, but held 30 *against* backward movement by means of a ratchet and pawl, and I do not broadly claim such a combination.

What I do claim as my invention, and desire to secure by Letters Patent, is—

35 1. A rotatable shaft, a pulley loosely mounted on the shaft but adapted to be connected to rotate therewith, a pinion secured to the shaft, a pinion loosely mounted on the shaft, means for preventing backward movement of 40 the last-mentioned pinion, a plate loosely mounted on the shaft, a pinion mounted on said plate and in mesh with the pinions here-

inbefore described, and a gear borne by the pulley and in mesh with the pinion on the plate.

45

2. A rotatable shaft, a pulley loosely mounted on the shaft but adapted to be connected to rotate therewith, a ratchet loosely mounted on the shaft, a pawl adapted to engage the ratchet, a pinion rigidly connected with the 50 ratchet, a pinion secured to the shaft, a plate loosely mounted on the shaft, a pinion mounted on the plate and in engagement with the pinions hereinbefore mentioned, and a gear on the pulley adapted to engage the pinion 55 on the plate.

3. A rotatable shaft, a pulley loosely mounted on the shaft but adapted to be connected to rotate therewith, said pulley having an internal gear, a ratchet loosely mounted on the 60 shaft, a pawl to engage the ratchet, a pinion rigidly connected with the ratchet, a pinion secured to the shaft, said pinions having a different number of teeth, a plate loosely mounted on the shaft, and a pinion mounted 65 on the plate and in mesh with said internal gear, and also with the pinions hereinbefore mentioned.

4. In a fast and slow motion mechanism, in combination, a rotatable shaft, a pulley 70 loosely mounted on the shaft, a clutch-section splined to the shaft and adapted to be engaged with the pulley, a pinion loosely mounted on the shaft, means for preventing backward movement of said pinion, a pinion secured to the shaft, a plate loosely mounted on the shaft, a pinion in engagement with said pinions hereinbefore mentioned, and a gear on the pulley in engagement with the pinion on the plate.

75 ALBERT B. TENNEY.
